UNITED STATES PATENT OFFICE.

ANDREW B. CAMDEN, OF DURANT, OKLAHOMA, ASSIGNOR, BY DIRECT AND MESNE ASSIGNMENTS, TO JOSEPH W. ALLEN AND S. H. ALLEN, BOTH OF TEMPLE, TEXAS.

TRAFFIC SIGNAL AND SIGNBOARD.

Application filed March 20, 1924. Serial No. 700,694.

To all whom it may concern:

Be it known that I, ANDREW B. CAMDEN, a citizen of the United States, residing at Durant, in the county of Bryan and State 5 of Oklahoma, have invented certain new and useful Improvements in Traffic Signals and Signboards, of which the following is a specification, reference being had to the accompanying drawings.

10 This invention relates to traffic signals or direction signs, and a particular object of the invention is to provide a structure of this character which is particularly adapted for use in villages, towns and cities for 15 the purpose of indicating street intersections and acting as a sign post for the streets leading therefrom.

15 A further object is to provide a device of this character which is also adapted to be used as a sign display device and which is adapted to support a number of signs in such manner that they will be particularly attractive and will be constantly changing.

20 A further object has to do with the details of construction and arrangement of parts as will appear more fully hereinafter.

25 My invention is illustrated in the accompanying drawings, wherein:—

Figure 1 is an elevation of a traffic signal 30 and sign board constructed in accordance with my invention, the base being partly broken away and the supports for the individual sign boards being in section;

35 Figure 2 is a sectional view on the line 2—2 of Figure 1;

Referring to these drawings, 10 designates a mast or like member, preferably of iron or steel pipe, which may be of any desired height as, for instance, seven feet, this mast 40 at its upper end being so formed as to support a lamp globe 11 carrying a lamp 12. The lower end of the tubular pipe which constitutes the mast or post is supported in a block 14 of concrete, this block preferably 45 having the form of a truncated pyramid so as to provide a number of upwardly and outwardly inclined faces 15 upon which traffic directions may be placed as, for instance, directions with regard to the speed limit or the distance and direction of a certain other town or village.

50 Mounted upon the upper end of the post are four arrows 16 or any desired number 55 may be used pointing in the direction of the four intersecting streets and containing the

names of the streets or other highway directions. Just below these four arrows are four larger sign boards 17 which are disposed at right angles to each other and which preferably terminate in pointing 60 hands, these sign boards having thereon traffic directions as, for instance, directions as to the speed limit or directions to keep to the right, left, etc. The posts or masts being hollow permit an electric wire 18 to pass 65 up through the mast or post or the wire may be taken from an overhead feed wire and brought down through an opening 19 in the upper end of the mast or post. The base 15 which, as before remarked, is of concrete, 70 may be held firmly down at any desired position by metal strips 20 which are set into the concrete and project beyond the same and have pins or screws 21 which may be driven down into the earth or other material of the roadway.

75 Rotatably supported upon the mast or post 10 is an elongated sleeve 22. This sleeve at its lower end is supported upon ball bearings 23, while the upper end of the 80 sleeve is supported in ball bearings 24. Mounted upon the sleeve 22 to rotate therewith are a plurality of upper and lower sets of radial arms 25, each pair of these arms supporting vertical shafts 26, the shafts being 85 free to rotate in the arms and the lower end of each shaft being supported in a cone bearing or equivalent member 27 carried by each lower arm.

90 Mounted upon the shafts 26 are the rotatable signs 18. These sign boards 28 are preferably two in number for each shaft, the edges of the sign boards being brought together and connected, as illustrated in Figure 2. The various signs may be painted or otherwise applied to these sign boards, and it will be obvious that if there is any wind all of the sign boards will slightly rotate around the post and each sign board 95 separately around the axis of its own particular shaft so that thus a very attractive advertising device is provided which will attract the eye instantly, which will give full information with regard to traffic rules, regulations, street intersections, crossings, etc., 100 and in which the advertisements may be 105 changed at any desired time.

I claim:—

110 In a device of the character described, a base, a stationary supporting shaft rising

from the base, a sleeve rotatable upon said shaft, upper and lower end thrust bearings for said sleeve, upper and lower spiders carried by said sleeve and rotatable therewith, 5 braces connected with elements of the lower thrust bearing and with the lower spider, the upper spider including arms formed with holes and the lower spider including arms formed with sockets, and sign plates 10 having upper and lower trunnions engaged within said holes and sockets respectively,

the upper edges of the sign plates terminating considerably below the upper spider whereby the sign plates may be moved upwardly to effect disengagement of the lower 15 trunnions from the sockets and may then be subsequently moved downwardly to disengage the upper trunnions from within said holes.

In testimony whereof I hereunto affix my 20 signature.

ANDREW B. CAMDEN.
